CLAIM

The ornamental design of a bow tie locking cotter, as shown and described.

DESCRIPTION

FIG. 1 is a top plan view of the bow tie locking cotter of our design, the bottom plan view being identical thereto;
FIG. 2 is a front elevational view of the bow tie locking cotter;
FIG. 3 is a rear elevational view;
FIG. 4 is a left side elevational view;
FIG. 5 is a right side elevational view;
FIG. 6 is an environmental perspective view;
FIG. 7 is an environmental reverse side perspective view;
FIG. 8 is a top plan view of an alternative design of our bow tie locking cotter, the bottom plan view being identical thereto;
FIG. 9 is a front elevational view;
FIG. 10 is a rear elevational view;
FIG. 11 is a left side elevational view;
FIG. 12 is a right side elevational view;
FIG. 13 is an environmental perspective view; and,
FIG. 14 is an environmental reverse side perspective view.
